RADIATOR FOR HOT AIR FURNACES

Elisha H. Scott, Richmond, Ind., assignor to The
Johnson Sheet Metal Works Corp., Richmond,
Ind., a corporation of Indiana

Application December 17, 1938, Serial No. 246,376

1 Claim. (Cl. 126—99)

This invention relates to improvements in hot air furnaces and more particularly to a novel radiator attachment therefor.

An object of this invention is to provide an improved radiator attachment of novel construction.

Another object is to provide a furnace radiator attachment which can be readily installed in the fluid heating chamber of a furnace. The heat radiator device may be connected in any furnace employed in fluid heating systems, for instance, air, or equivalent fluid heating systems.

Another object of this invention is to provide a radiator attachment for furnaces which greatly enhances the heating efficiency of the furnace by substantially increasing the heat radiating surface.

Another object is to provide a radiator having baffle means attached therein for causing the hot flue gases to circulate in the radiator before entering the stack.

Another object is to provide a novel and improved radiator which is inexpensive to manufacture and one which can be readily installed in conventional heating furnaces.

A still further object of this invention is to so connect the radiator in the air or fluid chamber of the furnace that the incoming fluid will be admitted adjacent the radiator through which the hot gases of combustion are conducted to the chimney. By this arrangement the advantages obtained are three-fold. First, in connection with hot air furnaces the incoming cold air will be heated more quickly. Second, the temperature of the gases passing into the stack will be greatly reduced, substantially increasing the life of the fluid conduits and stack connections. Finally, the overall heating efficiency of the furnace is decidedly improved.

Still another object of this invention is to provide an improved radiator construction and design which is capable of withstanding high temperatures as well as rapid heating and cooling with resultant expansion and contraction to which it is subjected during use.

In the drawings:

Figure 1 is a vertical section view taken through a hot air furnace embodying the improved radiator of this invention;

Figure 2 is a longitudinal section view taken on the line 2—2 of Figure 1, looking in the direction of the arrows;

Figure 3 is an elevation view of the radiator as viewed from the rear of the furnace;

Figure 4 is a similar view of the radiator on

a somewhat larger scale, as it appears from the front of the furnace;

Figure 5 is a plan view of the radiator partly in section and taken on the line 5—5 of Figure 4, looking in the direction of the arrows;

Figure 6 is a sectional view taken on the line 6—6 of Figure 5, looking in the direction of the arrows;

Figure 7 is a cross section view of the radiator and attached baffle plate taken on the line 7—7 of Figure 6;

Figure 8 is a perspective view of the forward half of the radiator showing the baffle member attached thereto.

Referring to the drawings in detail, the numeral 6 designates the outer casing of the furnace enclosing a furnace proper 7. The furnace comprises a firebox 8, grate 9, and ashpit 10. Fuel is introduced into the furnace through the door 11 and the member 12 permits entrance to the ashpit.

At the upper rear section of the furnace is an opening 13 to which is connected a short flue section 14, as shown in Figure 1. To this flue section is connected the radiator 15. The radiator attachment 15 comprises a distorted rectangular shaped hollow member forming a chamber through which the gaseous products of combustion pass before escaping to the atmosphere. Concentrically curved members 16 and 17 form the forward and rearward walls of the radiator. The opposed flanged edges of these members are secured together as by the rivets 18. It will be understood that the walls 16 and 17 of the radiator are curved to conform to the adjacent wall portions of the furnace and outer casing and that, in general, the radiator may be shaped to fit the particular space it is to occupy in the furnace.

An opening 19 in the wall 16 and aperture 20 of member 17 provide an entrance and exit respectively for the flue gases. From the exit 20 the gases are conducted through a conduit 21 which communicates with the stack or chimney 22. Near the bottom of the radiator is an opening 23 adjoining the conduit 24. The latter extends out through the furnace casing 6 and is provided with a cover plate 25 which is removable, allowing access to the bottom of the radiator for cleaning purposes.

Openings 19 and 20 are staggered so as to force the heated fluid gases to circulate, to some extent at least, through the radiator prior to entering the stack 22. Cold air ducts 26 open into the bottom of the casing 6 beneath the outer

ends of the radiator 15, as illustrated in Figure 2.

The radiator preferably is made of sheet metal, the walls of which are corrugated to provide a maximum heat radiating surface. This 5 construction also strengthens the radiator while affording greater resistance to distortion during expansion and contraction. It is understood, however, that if desired the radiator may be made by casting the same out of any suitable 10 material.

A novel and inexpensive way of constructing the radiator is shown in Figure 5, wherein the radiator comprises two cupped sections generally designated 27 and 28. Section 27 comprises a 15 curved corrugated wall member 16 having the arcuate shaped portions 29 and the connecting end walls 30. The other section 28 is made of the curved corrugated wall member 17 and end wall portions 31, as shown in Figure 5. Each of the 20 sections 27 and 28 comprises a straight-edged complementary flange portion 32 and 33, respectively.

These flanges extend around each section. The two halves are riveted, bolted, welded or otherwise secured together to form the radiator. The corrugations 34 are preferably formed in the wall members 16 and 17 during manufacture of the radiator. To fluid seal the radiator parts 27 and 28, the flanges 32 and 33 are welded as at 35. 30 Other means may be employed to form a fluid-tight radiator.

Suitably attached to the radiator member 27 is a baffle means 36 as illustrated in Figure 8. The baffle plate member forces the hot flue gases to circulate in the radiator before entering the stack, as indicated by the arrows on Figures 6 and 7.

The baffle member comprises a flat plate 37 which preferably is provided with longitudinal 40 and transverse ribs 38. The ends 39 and 40 of the plate 37 are curved to fit snugly against the walls 16 and 17 respectively, and the plate is secured to the opposed walls of the radiator at the flanged portions 41 and 42 by the bolts 43.

45 Adjacent the under side of the plate 37 are positioned the skirt members 44. Preferably these members are cut-away diagonally with respect to the sides of the plate 37 as at 45 and do not extend the full length of the plate as 50 shown in Figure 8. The skirt members 44 are not attached to the under side of the plate 37 but are welded or otherwise secured as at 46 to the wall 16.

This construction is optional, however, and if 55 desired the skirt members may be attached to the sides of the plate 37 or otherwise positioned

so as to force the flue gases to circulate downward, outward and upward centrally in the radiator prior to entering the stack. To accomplish this the skirt members 44 will preferably be positioned to form an obtuse angle with respect to the 5 under surface of plate 37, so as to force the hot gases to flow outward against the side walls of the radiator. This greatly increases the efficiency of the radiator.

The sections 27 and 28 of the radiator may 10 be suitably formed by die-pressing or cold-drawing of metal sheets, and the corrugations and apertures may be formed at the same time. Thereafter the sections are fastened together and sealed fluid-tight. Prior to riveting or fastening the members 27 and 28 permanently together 15 the baffle plate 37 will be secured to the wall 17 of the part 28. Optionally, however, the plate 37 may merely rest against the wall 17 without being bolted thereto. 20

The improved construction of the radiator, whereby the different sections can be united along a straight edge, provides an efficient and improved way of making a radiator of this character. Further, by reason of the straight-edge opposed flanges the radiator parts can be more readily assembled. Use of the ordinary riveting machines is afforded, which lowers the cost of manufacture. 25

It will be understood, of course, that this invention is not limited to the exact details of construction and use of the radiator device, since 30 obvious modifications and adaptations may be made by those skilled in the art, without departing from the spirit of this invention. 35

Having thus fully described my invention, what I claim as new and desire to secure by Letters Patent is:

A crescent shaped radiator for a hot air furnace comprising two cupped members, each member having a marginal flange lying in a vertical plane adapted to register with the other flange, means for attaching said flanges together, each member having a curved vertical wall, the vertical wall of one member having an outer convex surface, and the vertical wall of said other member having an outer concave surface, each of said members having top and bottom wall portions, said flanges when attached together extending closely adjacent to the medial top and bottom margins of said concave surface wall, and extending comparatively remote from the medial top and bottom margins of the opposite vertical wall. 40 45 50
